UNITED STATES PATENT OFFICE

2,309,107

PARACHUTE DEVICE

Guy E. Giroux, New York, N. Y., assignor, by
mesne assignments, to Aerial Products, Inc.,
New York, N. Y., a corporation of Delaware

Application October 18, 1939, Serial No. 299,916

7 Claims. (Cl. 244—145)

The present invention relates to a parachute device and it particularly relates to the small types of parachutes which are to be included in projectiles or containers to be elevated to substantial heights and caused to open and then release an object, such as an attached flare, which will descend slowly down to the ground.

It has not always been found satisfactory to form such parachute devices of paper materials, due to the fact that they are not strong as may be desired, require substantial sewing and also do not properly buoy the parachute and assure the slow desired rate of descent.

Moreover these paper parachutes have only limited power of suspended weight and will frequently overturn or collapse unless certain predetermined weights are placed thereon and they are not most desirable from the viewpoint of waterproofness, non-inflammable, moldproof character and dimensional stability under varying humidity and climatic conditions.

It is among the objects of the present invention to provide an improved parachute of the character above described which will be devoid of the disadvantages of paper parachutes and which will give a better suspension and a slower rate of descent with support of increased weight and which shall withstand packing, expulsion and/or any heat effect arising from the flare or other suspended object and which will maintain its balance and equilibrium during the descent without excessive oscillation.

Another object is to provide an improved small parachute device of the character above described, which will quickly snap itself to full inflated position when released without tendency toward overturning or collapsing even with very low weights suspended thereby, and which will be seamless and devoid of sewing, as soft and pliable as silk and as light as tissue paper, although it will possess much greater tensile strength.

Another object is to provide an improved parachute device of the character above described, which will be waterproof, non-explosive, non-inflammable, moldproof and have excellent dimensional stability throughout the entire humidity range.

Still further objects and advantages will appear from the more detailed description set forth below, it being understood, however, that this more detailed description is given by way of illustration, since various changes therein may be made by those skilled in the art without departing from the scope and spirit of the invention.

In accomplishing the above objects it has been found most satisfactory according to one embodiment of the invention to form the chute of a flexible plastic material, and preferably a flexible thermoplastic sheet material, such as for example sheet resins, sheet cellulose derivatives and preferably sheet rubber materials. The most satisfactory materials for the purpose of the present invention have been found to be rubber hydrochloride materials or chlorinated high molecular weight hydrocarbons. Combinations of these materials with or without plasticizers may also be employed.

It has been found most desirable to form a blank out of these sheet materials having a marginal portion with a plurality of spaced projections and a central portion, which central portion is distended by compression or stretching, as by a spherical or hemispherical form together with an electrical heater, hot air or a hot water jacket, to substantially spherical contour with substantial reduction in thickness.

The marginal portions at the same time will be as thick as the original sheet and to the projections extending from the marginal portions may be attached the strings for supporting the flare or other object to be suspended.

Referring to the drawings which illustrate several of the various possible embodiments of the present invention, but to which the present invention is by no means restricted, since the drawings are merely by way of illustration and not by way of limitation.

Fig. 1 is an elevational view of one form of parachute device according to the present invention,

Fig. 2 is a plan view of the blank of sheet material before it is formed into the parachute device of Fig. 1,

Figs. 3 to 5 illustrate one manner of forming the blank of Fig. 2 into the parachute of Fig. 1, Fig. 3 being a top plan view of the holder device for the blank, Fig. 4 being a transverse cross sectional view upon the line 4—4 of Fig. 3, and Fig. 5 being a side view illustrating how the holder is placed upon the forming device,

Figs. 6 and 7 illustrate an alternative method of forming the blank, Fig. 6 being a transverse sectional view showing the frame holding the blank before distension thereof and Fig. 7 showing the distension of the blank,

Fig. 8 is a diagrammatic transverse sectional view upon the line 8—8 of Fig. 1, upon an enlarged scale as compared to Fig. 1, and illus-

trating a variation in the thickness of the sheet material,

Fig. 9 is a transverse sectional view of an alternative forming arrangement.

Referring to Fig. 2, the blank A may be cut of any distendible thin or sheet material, which may preferably be thermoplastic, such as sheet rubber, sheet resins, sheet rubber hydrochlorides and particularly the sheet rubber chloride at present upon the market known as "Pliofilm."

The blank is cut out with the main flat central portion 10, which is to be distended into curved or distended shape, with the recesses 11 and with the projection 12.

In the final parachute, the central portion 10 is extended or distended so as to be of substantially less thickness and of hemispherical contour and is indicated at 10 in Fig. 1, while the edge or marginal portion 14 below the line at 15 is of substantially the original thickness.

The projections 12 may be tied together and gathered by the knot 13, to which is attached the cords 14, the ends 15 of which may suspend a flare or other device to be held in the air for a predetermined length of time.

Referring particularly to Figs. 3 and 4, the blank A, and particularly the marginal portion 14 thereof, is gripped between the upper annular block or plate 17 and the lower annular block or plate 18, the blank being held substantially flat.

At spaced intervals around the presser members 17 and 18 are positioned the clamps 19 having the lower clamping seat 20 and the upper clamping seat 21, which may be pressed down by the screw member 22.

When the blank A has been tightly gripped between the members 17 and 18, it is placed upon a distending or forming device, as shown in Fig. 5, which consists of a spherical glass bowl 23, which also may be of polished metal containing the heat resistance element 24, said bowl being supported on the base 25 and supplied by the electrical conduits 26.

The heat should be sufficient to cause the blank A to be distended into hemispherical form, as indicated in Fig. 1, with the seat of the clamping device C being sufficient to pull the blank A downwardly substantially past the middle point 15, as indicated for example at 23.

In the device shown in Figs. 6 and 7 (correspondingly functioning parts being indicated by the same numerals primed), the forming device D' is provided with an upper hemispherical forming section 23', which may be of metal or glass and the lower hot gas inlet section 27, which has an inlet nipple 28 connected to the valve 29.

The valve 29 connects to the inlet pipe 30, from which hot air may be admitted to the nipple 28 by actuation of the valve handle 31.

The hot air will force its way in, as indicated by the arrows 32 in Fig. 7, and press the blank against the inside face 33 of the globe D'.

The inlet portion 27 is provided with the flanges 34 which are held against the clamp elements 17' and 18' by the clamps E' having the screw members 22'.

In the device shown in Fig. 9 (correspondingly functioning parts being indicated by the same numerals provided with a superior 2), the clamping device E² receives an aluminum forming device D² which consists of the outer shell 35 and the inner shell 36 forming a jacket which is designed to receive hot water, steam or superheated air through the inlet 37, said jacket being also

provided with an outlet 38. This forming device D² may replace the forming device D, as shown in Fig. 5. Cold water or cool fluids may also be introduced for quick cooling after the heat 5 distention has taken place.

In Fig. 8 is shown how the material becomes much thicker in passing from the distended hemispherical portion at 10 into the marginal portion at 14, after it has been formed into a 10 parachute.

It is thus apparent that the present applicant has provided an improved parachute, which, due to its hemispherical form, will have an enhanced power to suspend weight much superior to conical 15 parachutes, or parachutes which may be sewn from sectors of paper.

The hemispherical chute of the present application has a superior weight suspending power in direct proportion to its greater inside surface 20 area and its suspending power is further augmented by lowering its base line to a point substantially below the line 15, which is the diameter line of the hemisphere.

It is noted that the parachute is so constructed 25 that its thinnest and lightest surface area is at the top and by increasing the thickness of its walls by consistent progression from its apex to its base line, its greatest gravity pull will be positioned at the bottom.

30 The result is that the parachute when dropped a shorter distance, as from the ceiling of an average room, will fall in normal descending position without other ballast than that provided by the weight of its own shroud lines, whereas 35 a conical parachute so dropped would quickly overturn and collapse in its descent.

The present parachute may be quickly snapped upwardly from an inverted position on the floor and when released will right itself in the air, 40 slowly settling back to the floor in normal descending position.

Even as small a parachute as of 12" true diameter, when fired to a height of 150 feet, carrying a two-ounce flare, will descend not more than 45 half way to the ground during the interval required to burn out the flare.

It will be noted that the parachute has the 50 important advantage of being seamless, and forming a perfect hemisphere when distended. Although it is as light as tissue paper, it possesses much greater tensile strength.

The material from which it is made is as soft 55 and pliable as silk, is waterproof, non-explosive, non-inflammable, moldproof, and has excellent dimensional stability throughout the entire humidity range.

If desired, instead of being formed of a single 60 sheet of material, the parachute may be formed of several sheets which may be wrapped together and welded or fused together at the laps.

65 By arranging the strength and thickness of the material, diameters even up to 16 feet may be obtained.

Due to the flexibility and elasticity of the sheet 65 material, it is also possible to even cause the marginal portion 14 to be re-entrant and to have a smaller spacing below the line 15 or 15' than at the line 15 or 15' and then, if desired, the lower portion may flare outwardly adjacent the projections 12.

70 Although the hemispherical form is preferred, it is also possible to use a closed bottom cylindrical or even elliptical shapes. However, the hemispherical form appears to give the greatest 75 buoyancy and seems to be most satisfactory.

It will be noted that in Fig. 9 the lower marginal portions 14² of the sheet A² closely conform to the lower portions of the walls of the jacket D², with the result that the heating will be applied uniformly over the entire distended area 10². It is found for certain purposes this gives a more satisfactory result than to have the marginal portion separated from the heated surface, as indicated in connection with the marginal portions 14 in Fig. 5.

Of course, the clamp C of Fig. 5 and C² of Fig. 9 might be so arranged as to permit conformation of the marginal portions 14 and 14² to re-entrant portions of the globe D or inturned portions which may be formed upon the jacket D².

As many changes could be made in the parachute device, and many apparently widely different embodiments of this invention could be made without departing from the scope thereof, it is intended that all matter contained in the above description shall be interpreted as illustrative and not in a limiting sense.

What is claimed is:

1. A parachute formed of a thermoplastic sheet material having relatively thick marginal portions and a relatively thin domed portion.

2. A parachute formed of sheet rubber having relatively thick marginal portions and a relatively thin domed portion.

3. A parachute formed of chlorinated high molecular weight hydrocarbon material having relatively thick marginal portions and a relatively thin domed portion.

5. A parachute formed of a thermoplastic sheet material having relatively thick marginal portions and a relatively thin domed portion of hemispherical contour.

10. A parachute formed of a thermoplastic sheet material having relatively thick marginal portions and a relatively thin domed portion, the latter being distended into permanent hemispherical conformation.

15. A parachute formed of a thermoplastic sheet material having relatively thick marginal portions and a relatively thin domed portion, the latter being stretched into permanent hemispherical conformation.

20. A process of forming a parachute device which comprises forming a circular blank of a sheet thermo-plastic material with a scalloped edge, attaching weighting means to the scalloped edge and then placing the central portion of the blank on a heated spherical member and permitting said weighting means to distend the central portion of said blank by their weight while said blank is applied to said heated member.
